UNITED STATES PATENT OFFICE.

JOHN H. DALE, OF NEWARK, NEW JERSEY, ASSIGNOR OF TWO-THIRDS
TO FRANK MARSH, OF NEWARK, NEW JERSEY, AND RALPH R. HOYT,
OF NEW YORK, N. Y.

ICE-BREAKING DEVICE.

No. 821,927.

Specification of Letters Patent.

Patented May 29, 1906.

Application filed October 21, 1904. Serial No. 229,363.

To all whom it may concern:

Be it known that I, JOHN H. DALE, a citizen of the United States of America, residing in the city of Newark, county of Essex, and 5 State of New Jersey, have invented certain new and useful Improvements in Ice-Breaking Devices, of which the following is a specification.

The object of this invention is to provide 10 an inexpensive, portable, and efficient device for breaking ice for use in bars, hospitals, &c.

It comprises an organization involving two 15 rotary ice-breakers, from the first of which the broken ice passes to the second, where it is further reduced in size. A means of adjustment is provided whereby the ice may be reduced or broken into pieces of different size, as may be desired.

In the accompanying drawings, Figure 1 is 20 a view, mainly in vertical section, on the line 1 1 of Fig. 2 with the sides of the hopper or receptacle for disintegrated ice broken away. Fig. 2 is a front view in vertical section at right angles to Fig. 1; Fig. 3, a plan; Fig. 4, 25 a section on the line 4 4 of Fig. 2; Fig. 5, an end elevation of the upper rotary member carrying ice-breaking points; Fig. 6, a plan of the same broken away or in section at one point; Fig. 7 a plan, and Fig. 8 a side elevation, of the lower tooth-carrying or ice-breaking member.

The casing may be as shown or of any appropriate construction and comprises a hopper *a* at the top and a broken-ice receptacle *b* 30 at the bottom, the latter forming a base from the corners of which apertured lugs *b'* extend for the purpose of attaching the device to suitable support, as a table or shelf. At the base of the hopper and in suitable bearings 35 formed in the sides of the casing or upper walls is mounted a shaft *c*, with a key or feather. To one projecting end thereof is applied a crank-wheel *d* and to the other a bevelled gear *e*. To this horizontal shaft are 40 keyed trefoil collars *f*, having three equidistant projections *f'*, in the contiguous faces of which are formed seats *f''*, in which are seated pointed ice-breaking teeth or picks *g*, all pointing in the direction of rotation and 45 shown as arranged on lines tangential to circles struck from the axis of rotation. The several collars—eight being shown—are clamped to bind the picks *g* in their seats by

three bolts and nuts *h* passing through the three projections *f'* of each collar *f*. By loosening the nuts the extent of projection of the teeth may be adjusted. Opposite the pick-head, so formed and preferably slightly below the axis of rotation thereof are inwardly-projecting teeth *i*, mounted in the wall at the 55 base of the hopper and held by set-screws *i* or otherwise and projecting into the spaces between the teeth *g*. The front wall of the hopper is preferably inclined, as shown, to direct the block of ice to the picks or teeth *g*. 60 The ice broken by these teeth in pieces sufficiently small will pass down between the horizontal stationary teeth *i*, while pieces too large to pass will be broken between the revolving and stationary teeth. The bevelled 65 gear *e* meshes with a corresponding gear *j* on a vertical shaft *j'*, to which it is splined, so that the shaft may be vertically adjusted by means of nuts applied to its upper threaded 70 end on each side of a bracket *k*, projecting from the side of the hopper. The shaft has its bearing in this bracket and also in a boss *k'*, projecting upwardly from the casing and in a cross-piece *k''*, extending between the 75 walls of the casing. Below the bottom of the 80 hopper the casing inclines laterally, and at the bottom of the inclination is a circular opening *m*, the downwardly-extending walls of which flare outwardly and have formed upon their inner face projecting teeth *n*. In 85 the conical chamber thus formed and opening into the receptacle *b* is located a conical pick-head, which is shown in detail in Figs. 7 and 8. It is composed, as shown, of five 90 separate sections or collars *o*, applied to the reduced lower end of the shaft *j* and clamped together by a washer-nut *p*, applied to the 95 threaded end of the shaft. The several collars are of different radial dimensions, and each one has three projections *o'*. In contiguous faces of such projections are seats for the picks *q*, arranged radially with reference to the axis of rotation and the projection of which may be adjusted by loosening the nut *p*. By adjusting the conical picker-head 100 vertically in the conical chamber *m* the picks carried by the head and the points on the interior surface of the chamber may be brought closer together or farther apart to break the ice to the desired degree. After passing the 105 conical picker-head the ice drops into the re-

ceptacle b , which is provided with a suitable sliding drawer b^2 . The receptacle may be composed of metal, cast or otherwise formed, and the drawer may be made of ordinary galvanized sheet-iron. The hopper and inclined part of the casing may be cast in one piece and bolted on the top of the receptacle.

I claim as my invention—

1. In an ice-breaking device, the combination of a hopper having an inclined wall at the base of which is disposed a picker-head revolving about a horizontal axis and having projecting teeth, a series of fixed teeth between which the teeth upon the picker-head pass, a receptacle for broken ice, a section of inclined casing extending from the base of the hopper to the receptacle and terminating in a circular outwardly-flaring conical opening having ice-breaking teeth upon its inner surface, a tapered picker-head disposed in said conical chamber and carrying teeth projecting therefrom, a vertical shaft upon which the lower picker-head is mounted, bearings therefor, a beveled gear splined thereto and a corresponding beveled gear on the shaft of the horizontally-disposed picker-head, and means for adjusting the shaft of the tapered picker-head, for the purpose set forth.
2. In an ice-breaking device, the combination of a hopper having an inclined wall at the base of which is disposed a picker-head revolving upon a horizontal axis and having projecting teeth, a series of fixed teeth between which the teeth upon the picker-head pass, a receptacle for broken ice, a section of inclined casing extending from the base of the hopper to the receptacle and terminating in a circular outwardly-flaring conical opening having ice-breaking teeth upon its inner surface, a tapered picker-head disposed in said conical chamber and carrying teeth projecting therefrom, a vertical shaft upon which the lower picker-head is mounted, bearings therefor, a beveled gear splined thereto and a corresponding beveled gear on the shaft of the horizontally-disposed picker-head, and means for adjusting the shaft of the tapered picker-head, for the purpose set forth.

2. In an ice-breaking device, the combination of a hopper having an inclined wall at the base of which is disposed a picker-head revolving upon a horizontal axis and having projecting teeth, a series of fixed teeth between which the teeth upon the picker-head pass, a receptacle for broken ice, a section of inclined casing extending from the base of the hopper to the receptacle and terminating in a circular outwardly-flaring conical opening having ice-breaking teeth upon its inner surface, a tapered picker-head disposed in said conical chamber and carrying teeth projecting therefrom, a vertical shaft upon which the lower picker-head is mounted, bearings therefor, a beveled gear splined thereto and a corresponding beveled gear on the shaft of the horizontally-disposed picker-head, and means for adjusting the shaft of the tapered picker-head, for the purpose set forth.

In testimony whereof I have hereunto subscribed my name.

JOHN H. DALE
